Application February 4, 1937, Serial No. 123,984

3 Claims. (Cl. 229—6)

This invention relates to the fabrication of boxes made from materials of the nature of cardboard, pasteboard and bristolboard or like sheet paper and strip fibrous stock; especially to the fabrication of such a box when composed of a container member and a cover member each including a side strip of paperboard stock covered with finish paper, and each member including a false bottom element, or a false top element, as the case may be, with only the exposed inner face of such element finished, each of the elements being completed by a mask or decorative outer part made separately of sheet material and secured to the false bottom member or the false top member in such a manner as to present a peripheral flange or rim of an ornamental character projecting beyond the edge at which the side strip joints the bottom or top components.

The invention is of particular utility when used in the fabrication of fancy boxes for holding candy or for like uses, such as the highly colored, heart-shaped boxes popularly identified with St. Valentine's Day offerings, although the basic idea of means underlying the invention is susceptible of many other physical embodiments.

The principal object of the invention is to provide a box structure which may be fabricated at a relatively low cost and which is substantially a replica of more expensively made boxes of the last-named type, and to produce a box which is equally attractive in appearance and desirably sturdy in structural composition, thus making it possible to create a wider market than can be found for the more expensive boxes of conventional construction.

Another object of the invention is to provide a box structure which is the product of a novel method of fabrication including a step of perfecting a heat-molded union at the edge of the box where the strip constituting the side wall is adjoined to the bottom wall of the container, or to the top wall of the cover, as the case may be, and thereby to make available for use as the side wall component a continuous composite strip of the heavy paper stock with its finish surface ply of superior paper giving both sides of the side wall an ornamental finish.

A cognate object is to provide a stock strip for use in making the side walls of such boxes which can be made up of indefinite length and severed to supply a side wall part for any desired size and shape of box, the strip being of uniform width and having smooth, unbroken edges throughout its length, being also capable of use without any

preparation to fit it to a given size of box, in accordance with this invention.

Other objects and features of the invention will appear as the description of the particular physical embodiment selected to illustrate the invention progresses.

In the accompanying drawings, like characters of reference have been applied to corresponding parts throughout the several views which make up the drawing, in which:

Fig. 1 is a plan view of a heart-shaped candy box in the construction of which the present invention has been embodied, parts being broken away;

Fig. 2 is a fragmentary, detail view in vertical section, on a larger scale, taken on the line 2—2 of Fig. 1;

Fig. 3 is a fragmentary, detail view of the side wall strip component as severed from the roll of stock strip from which is derived the supply for fabrication of side walls both of the container member of the box, and of the cover member thereof, the severed part shown being bent to its approximate final shape, and having its ends stitched together.

Fig. 4 is a fragmentary, detail view in vertical section, similar to Fig. 2 and illustrating a preliminary step in the assembly of the wall strip of Fig. 3 with other elements of the cover member of the box shown in Fig. 1;

Fig. 5 is a view similar to Fig. 4, but showing all of the cover elements assembled and adhered in molded juxtaposition, at a typical cross-section of the box side wall, having been taken on the line 2—2 of Fig. 1.

Fig. 6 is a view on a reduced scale of a supply roll of the composite side-wall strip.

In a now-preferred embodiment of the invention selected for illustration and description, the reference character A designates generally a heart-shaped candy box, of which the member designated generally by the reference character B is the lower, or container, part of the box, and the member designated C is the cover part (see Fig. 2).

Each of these members or parts comprises as components a sidewall, as W, W', which, in pursuance of the invention is made up from a supply strip of stock of composite character, from which a suitable moiety is severed, then is bent to approximately the contour intended for the box in course of fabrication, as indicated at W (Fig. 3), and may have its free ends secured together, as by a metal stitch.

The supply strip for this side wall component

is composed, according to the invention, of a foundation element of relatively heavy paper stock, such as Kraft paper, which is of uniform width, and has unbroken, smooth longitudinal edges, throughout the length of the stock strip and of every moiety thereof. This strip is numbered 12.

To one face of this foundation is adhered a facing or reinforcement strip 13, of somewhat stiff paper material, sufficiently narrower than the foundation strip 12 to leave exposed, along one longitudinal margin thereof, as at 14, a free zone or edge, which is adapted to be bent angularly with respect to the inner face of the foundation strip, and to be molded by heat and pressure, suitably applied, to constitute an attaching flange by which the side wall is united to the bottom components, or top components, of the container B, or of the cover C, as the case may be, as at 18 (see Fig. 4).

The structure of the composite side wall strip also includes preferably a facing strip of paper or other suitable material, 15, which is desirably of superior finish, as compared with that of the foundation strip, and which may be of lighter paper, as for example a light gilt paper strip, in the instance illustrated, the gilt facing shown extending over the outer face of the foundation and around the edge 16, which is to be the free edge of the cover member C, and also extending, as at 15x, preferably to about the region of the inner surface of the side wall indicated by the line 17 in Figs. 3 and 4.

I have found it desirable to terminate this facing strip somewhat short of the edge 18 of the heavy foundation strip, as indicated to 19, inasmuch as the molding of this edge and its adherence to the contiguous bottom or top components is usually accomplished more effectively when the edge 18 is substantially free. This, however, is not an indispensable provision.

The fabrication of the container member of the box, according to the method of the present invention, is carried out in the same manner as the fabrication of the cover member, so that the operation will be described in detail only with reference to the steps involved in making the cover, as shown in Figs. 3, 4 and 5.

A suitable length of the composite side wall strip W, such for example as that shown in Fig. 3, having been provided, and preferably stitched together at its free ends, as at 11, for convenience in manipulation, this side wall component is bent into the approximate shape of the box to be fabricated, and the side wall element thus constituted is assembled in circumjacent relation with a suitably shaped disc 21 of appropriate stock, such as cardboard, which need be finished only on its free face, the disc preferably being of a size suitable to fit snugly within the confines of the heavy foundation ply 12 as shown most clearly in Figs. 4 and 5.

This snug fit is advantageous in the respect that the disc is thereby caused to overlap the edge 13x of the ply 13, which serves as an abutment for the disc and aids in creating a tight joint around the inner corner edge of the cover.

At this stage of the operation, the side element W stands with its margin 14 in upright position, as shown in Fig. 4, ready to be bent over into the position shown in Fig. 5, at 18, this step being accomplished by suitable means, such as a hand tool, or a set of dies, (not shown), by which the margin 14 of the side wall element is molded by pressure, preferably with heat adequate to crimp

the flange thus formed into permanent overlying relation with the contiguous margin of the disc 21.

Adhesive is then applied, as indicated at 20, over the upper surface of the flange 18 and the adjoining marginal surface of the disc 21, and the cover member is completed by superimposing a mask or decorative top element upon the gummed flange and underlying disc 21, and pressing the assembled parts into close juxtaposition until the adhesive shall have become set.

As already indicated, the lower member, or container, B, is formed in identical fashion, and of proper size to have the completed cover member C fitted telescopically in complementary relation therewith, which completes the box.

Various advantages proceed from the fabrication of such boxes according to the above disclosed novel method of the present invention, among which may be cited the fact that the several members of the box elements can be pre-formed, each with its foundation component and its facing of superior finish material, so that the delicate operation of adhering relatively flimsy colored paper, as that illustrated at 15, need not be performed after a box member is assembled.

Again, the crimping of the side wall component flange 14 can be effectively and rapidly accomplished without first applying any adhesive, so that a tightly molded joint between the side wall and false bottom 21 is provided before application of the adhesive 20, and as the latter is applied only to a flat area of any member, there can be no extravasation of adhesive through the peripheral corner seam, into the box.

While we have illustrated and described the best form of the invention now known to us, it is to be understood that the particular embodiment illustrated does not exhaust the possible physical embodiments of the idea of means which underlies the invention.

We claim:

1. A composite stock strip for use in forming side wall components in the fabrication of boxes of the class described: said composite strip consisting of a uniformly wide foundation ply of relatively heavy fibrous stock of indefinite length, having smooth, unbroken edges throughout its length; a ply of somewhat stiff, fibrous stock adhered to a face of said foundation ply, leaving free a longitudinal margin of the latter; and a ply of lighter material of superior finish adhered to, and constituting a facing for, that edge and the adjacent margins of the composite strip which form the free edge of the side wall of a box member; the other longitudinal edge and adjacent margins of said heavy foundation ply being exposed beyond said finish ply and being deformable under heat and pressure to constitute a crimped flange by which to effect attachment of said side wall strip to a bottom or top element of the box, selectively.

2. A composite stock strip for use in forming side wall components in the fabrication of boxes of the class described: said composite strip adapted to be included in the fabrication of a box member and consisting of a uniformly wide foundation ply of heavy Kraft paper stock of indefinite length, having smooth, unbroken edges throughout its length; a ply of somewhat stiff paper stock, finished on one face and adhered by its other face to a face of said Kraft ply; and a ply of thin, highly colored paper stock adhered to, and constituting a finish for, that edge and the adjacent margin of the outer face of said Kraft paper ply.

which form the free edge of the side wall of a box member.

3. A composite stock strip for use in forming side wall components in the fabrication of boxes of the class described; said composite strip consisting of a uniformly wide foundation ply of relatively heavy fibrous stock of indefinite length, having smooth, unbroken edges throughout its length; a ply of somewhat stiff, fibrous stock adhered to a face of said foundation ply, leaving a free a longitudinal margin of the latter; and a 10 ply of lighter material of superior finish ad-

hered to, and constituting a facing for, that edge and the adjacent margins of the composite strip which form the free edge of the side wall of a box member; the other longitudinal edge and adjacent margins of said heavy foundation ply being exposed beyond said finish ply and being deformable to constitute a crimped flange by which to effect attachment of said side wall strip to a bottom or top element of the box, selectively.
